UNITED STATES PATENT OFFICE.

FRED R. SOMMER, OF BROOKLYN, NEW YORK.

MICROMETER ADJUSTMENT.

Application filed June 15, 1920. Serial No. 389,108.

To all whom it may concern:

Be it known that I, FRED R. SOMMER, citizen of the United States, residing at Brooklyn, in the county of Kings and State 5 of New York, have invented certain new and useful Improvements in Micrometer Adjustments, of which the following is a specification.

This invention relates to an improved 10 micrometer adjustment for microscopes, telescopes and other scientific instruments.

Heretofore the relative adjustment between two telescopic sections or parts of many scientific devices has been maintained 15 by relying on the frictional engagement between the parts but this is objectionable because it is almost impossible to shift to a minute degree. Also, an alternative method utilizing a rack and pinion for adjustment is likewise objectionable because of the comparatively great expense of cutting the toothed parts while at the same time these elements offer an obstruction on the exposed portions of the instruments 20 which are in the way and otherwise a source of annoyance.

Accordingly, a primary object of the invention is to provide a simple and convenient means which may be readily manipulated to move the relatively shiftable parts 30 of scientific instruments with a maximum degree of accuracy which is essential to obtaining reliable conclusions in scientific investigations. In this connection it is proposed to provide a construction of a simple 35 mechanical nature that can be made without the use of special tools or expensive equipment, thus enabling the cost of this feature of instruments of a character requiring such 40 adjustments to be materially reduced, while at the same time generally simplifying assembly and the mode of operation.

It will therefore be apparent that the present invention aims to provide a simple 45 and compact arrangement whereby the desired adjustment may be easily effected with a maximum degree of efficiency.

Other objects will appear as the description proceeds.

50 A preferred and practical embodiment of

the invention is shown in the accompanying drawings in which:

Figure 1 is a view partly in section and partly in elevation illustrating the present improvements.

Figure 2 is a cross section on the line 2-2 of Figure 1.

Similar reference characters designate corresponding parts throughout the several figures of the drawings.

The present invention is susceptible of a wide range of application to instruments requiring minute and accurate adjustments, such for instance, as microscopes, telescopes, levels and other instruments, and by way of illustrating one application thereof reference may be made to the drawings wherein the improvements are shown in connection with a microscope for the purpose of varying the distance between the eye-piece and the objective end. In the embodiment shown, the main tube or casing 1 may be frictionally held within the bore 2 of a supporting arm 3 by a suitable clamping bolt inserted in the opening 4 of the yielding jaws 5. Obviously by tightening and loosening the clamping bolt the jaws of the clamp may be manipulated to permit the main tube to be quickly adjusted to any desired position, and thereafter further adjustments may be made with great accuracy through the utilization of the present improvements.

Referring more particularly to the novel features of the present improvement it will 85 be observed that the main casing 1 is externally threaded as at 6, the said threads being either of the single or multiple thread type, while its side wall has therein a slot 7 which may be of the straight formation 90 shown or spiral formation to constitute a guide or run-way for the nut 8 or its equivalent which is preferably held as at 9 to the body of the interior tubular member 10 that telescopically slides within the casing 1.

The said interior member 10 is preferably provided with a suitable collar 11 adapted to be engaged by a novel shifting nut 12 in such a manner that the said member may be accurately moved with reference 100

to the casing 1. And, the shifting nut 12 is exteriorly milled as at 13 to afford a convenient finger grip, while its interior is threaded as at 14 to engage with the threads 6 of the main casing 1. Also, the said nut 12 is provided with an annular interior abutment shoulder 15 for engaging with one side of the collar 11 while the upper end of the nut has fitted thereto a relatively 10 separable locking ring 16 for engaging with the side of said collar 11 opposite the abutment shoulder 15. The ring 16 therefore cooperates with the annular abutment shoulder 15 to lock the interior tubular member 15 with the nut in such a manner that when the nut is rotated on the threads 6 of the main casing the interior tubular member will be shifted longitudinally with reference to the main casing.

20 The locking ring 16 previously referred to is preferably provided with a scale S on its exposed surface for registering with suitable markers M on the interior casing member so that the degree of movement of the nut may be readily determined to properly shift the interior member with reference to the outer tubular member or main casing 1. As a part of the means for adjusting the relative position of the two members the guide nut 8 25 which is carried with the interior tubular member is provided with a zero marker to be read in connection with a scale S' formed along the edge of the slot 7. By means of the scales S and S' the relative movement 30 between the two members may be accurately determined, according to the unit of measurement represented by the divisions of the respective scales.

From the foregoing it will be apparent 40 that the present improvement essentially contemplates a relatively fixed casing 1 and a relatively shiftable interior member which may be shifted with reference to the said casing by means of a rotatable adjusting device in the form of the nut 12 which is locked with the interior tubular member and has a threaded engagement with the outer main casing member 1. By simply manipulating the nut 12 in a clock-wise or counter clock-wise direction the interior tubular member 50 may be accurately shifted the distance of a hair line to obtain the desired results.

Without further description it is thought that the features and advantages of the invention will be readily apparent to those skilled in the art, and it will of course be understood that changes in the form, propor-

tion and minor details of construction may be resorted to without departing from the spirit of the invention or scope of the appended claims.

I claim:

1. An adjustment device of the class described including a pair of relatively telescoped members, an abutment on one of said members and feeding threads on the other member, and a sleeve having collars engaging both sides of said abutment and also engaging with said feeding threads. 60
2. An adjustment device of the class described including a pair of relatively telescoped members, an annular abutment on one of said members and feeding threads on the other, and a sleeve having threads for engaging with the feeding threads of one member and means for engaging with both sides of said annular abutment. 70
3. An adjustment device of the class described including a relatively fixed tubular member having a slot and feeding threads at one end thereof, a relatively shiftable tubular member telescoping within the fixed member, a guide projection carried by the shiftable member for riding in said slot, 80 an annular abutment also on said shiftable member, a sleeve having interior threads for engaging with the said feeding threads and also having an interior annular abutment engaging shoulder, and a fastening ring detachably secured to said sleeve at one side of the said shoulder to provide a channel for rotatably receiving the annular abutment on the shiftable member. 90
4. An adjustment device of the class described including a relatively fixed tubular member having a guide slot and feed threads, a shiftable member telescoping within the said tubular member and having a guide projection, a scale arranged along 95 the edge of the guide slot and cooperating with a zero marker on the guide nut, a sleeve interlocked with said shiftable member and having a feeding engagement with said threads on the tubular member; and a scale 100 marker on the sleeve and adapted to read in connection with the scale markers on the circumference of the shiftable member. 105

In testimony whereof I hereunto affix my signature in the presence of two witnesses. 110
